JOSEPH CHASSAING, OF ST. LOUIS, MISSOURI, ASSIGNOR TO SHIRAS ELECTRIC COMPANY, OF ST. LOUIS, MISSOURI, A CORPORATION OF MISSOURI.

ELECTRIC-LAMP BRACKET.

1,114,110.

Specification of Letters Patent. Patented Oct. 20, 1914.

Application filed March 16, 1914. Serial No. 824,961.

To all whom it may concern:

Be it known that I, JOSEPH CHASSAING, a citizen of the United States, residing at the city of St. Louis, State of Missouri, have 5 invented a certain new and useful Improvement in Electric-Lamp Brackets, of which the following is a full, clear, and exact description, such as will enable others skilled in the art to which it appertains to make 10 and use the same, reference being had to the accompanying drawings, forming part of this specification, in which—

The figure represents a detail view in perspective of my improved electric lamp 15 bracket.

This invention relates to a new and useful improvement in electric lamp brackets, the object being to construct a device of the character described which is simple, cheap, 20 and one which is portable, enabling the lamp to be supported by a stand or upon a bed such as is commonly used in hospitals, hotels, and the like.

In the drawings, 1 indicates the portable 25 member of a lamp stand, the upper end of which is provided with a cross-piece 2 having knobs at each end. It is obvious that this cross-piece might represent the horizontal member of a so-called iron or brass bed, and 30 the vertical rod of the stand, one of the vertical members of the head or foot of the bed.

3 indicates a bracket member whose upper end is bent to engage the horizontal member of the stand or bed as the case may 35 be, the vertical leg of said bracket extending down and having removably secured thereto a U shaped clip 4. This clip should extend out sufficiently to center in the arch of the bent upper end, whereby to hold the bracket 40 member vertical. This clip is held in position by a screw, thus enabling different sized slips or U-shaped members to be used on the bracket member depending upon the diameter of the horizontal member of the 45 bed and the size of the vertical rod with which the clip co-operates. The lamp is placed in position on a bed or stand by simply hooking the bent end of the bracket over a horizontal member, and engaging the 50 clip with a vertical rod, thus dispensing with the use of any thumb screws or clamps.

5 indicates a post mounted in the lower end of the bracket by means of a screw whereby the same may be rotatably adjusted. The outer end of this post forms a 55 hinge member 6 in which a co-operating hinge member 7 is arranged, these two hinge members being held together by a pin-tle screw 8 whereby the lamp may be adjusted at any angle inwardly and outwardly 60 with respect to the bracket.

9 is the socket member of the lamp into which the wires 10 lead, the usual socket switch being controlled by a pull cord 11.

12 is a globe of the lamp.

It will be seen that the device is portable and can be carried from place to place, the wires terminating in a plug whereby it may be connected to the line circuit quickly and easily. It is especially adapted for hospital use and may be arranged on a bed or on a stand as desired, being placed in position by a simple operation not necessitating the manipulation of any screws or clamps.

What I claim is:

1. An electric lamp bracket comprising a hooked member adapted to engage a horizontally disposed support and having means for engaging a vertical member whereby the bracket is prevented from lateral movement, and a lamp adjustably mounted on said bracket.

2. An electric lamp bracket comprising a vertical member having a hook at its upper end, a U-shaped clip carried by said bracket, and a lamp also carried by said bracket, said lamp being adjustable with respect to the bracket.

3. A portable lamp bracket comprising a hooked member having a U-shaped clip removably secured therein, a post rotatably mounted therein, and a lamp hinged to the outer end of said post.

In testimony whereof I hereunto affix my signature in the presence of two witnesses, this 5th day of March 1914.

JOSEPH CHASSAING.
